UNITED STATES PATENT OFFICE.

EDGAR A. RUSSELL, OF WALLINGFORD, CONNECTICUT.

DESIGN FOR A SYRUP-CUP COVER.

SPECIFICATION forming part of Design No. 29,124, dated August 2, 1898.

Application filed June 27, 1898. Serial No. 684,627. Term of patent 7 years.

To all whom it may concern:

Be it known that I, EDGAR A. RUSSELL, of Wallingford, in the county of New Haven and State of Connecticut, have invented and produced a new Design for a Cover for Syrup-Cups; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a syrup-cup cover embodying my design; Fig. 2, a bottom plan view thereof.

My invention relates to a design for covers for syrup-cups; and the design consists in the form of the cover, as hereinafter described, and shown in the accompanying illustrations.

As herein shown, my newly-designed cover

for syrup-cups consists in a dome-like body portion A, having its lower portion contracted, as at B, and then turned outward to form a flange C. The cover also comprises a flat arm D, extending from its lower edge and provided with two downwardly-turned perforated lugs E and with an upwardly-turned finger-piece F, all as shown in the accompanying illustrations.

I claim—

The design for a syrup-cup cover substantially as shown and described.

In testimony whereof I have signed this specification in the presence of two subscribing witnesses.

EDGAR A. RUSSELL.

Witnesses:

FRED. C. EARLE,

GEORGE D. SEYMOUR.
